UNITED STATES PATENT OFFICE

167,454

COFFEE-MAKING MACHINE

Abram Games, London, England, assignor to
"Cona" Ltd., London, England

Application September 15, 1951, Serial No. 16,662
In Great Britain April 18, 1951

Term of patent 14 years

(Cl. D44—26)

To all whom it may concern:

Be it known that I, Abram Games, a subject of the King of Great Britain, and residing at London, England, have invented a new- original, and ornamental Design for a Coffee Making Machine, of which the following is a specification, reference being made to the accompanying drawings, forming part thereof.

Fig. 1 is a side perspective view of a coffee making machine showing my new design;

Fig. 2 is a top plan view;

Fig. 3 is an elevational view of the handle side; and

Fig. 4 is a bottom plan view thereof.

I claim:

The ornamental design for a coffee making machine, substantially as shown.

ABRAM GAMES.
